AUTOMATICALLY COMPENSATING GUN
SIGHTLouis W. Greenblatt, Jr., and Guy T. Bixby,
Dayton, Ohio

Application September 5, 1941, Serial No. 409,704

7 Claims. (Cl. 33—49)

(Granted under the act of March 3, 1883, as
amended April 30, 1928; 370 O. G. 757)

The invention described herein may be manufactured and used by or for the Government for governmental purposes, without the payment to us of any royalty thereon.

This invention relates to a control apparatus for directing the fire of a gun when there is relative movement between the gun platform and the target, and especially when the speed of relative movement is great.

It is an object of this invention to provide in a fire control apparatus a device for constantly measuring the relative speed between the gun platform and the target, and apparatus associated therewith and operated thereby for maintaining the gun in an alignment which allows for the factor of time of flight of the projectile and for other factors affecting the flight of the projectile, such as ballistic and wind effects.

It is a further object of this invention to provide a sighting apparatus which, by maintaining the sight on the target, will enable training of the gun toward the predicted position of the target or, in other words, where the target will be when the bullet strikes it.

It is another object of this invention to provide a tachometer device for measuring relative speed between the target and the gun platform and sight-operating means associated therewith, which responds directly and proportionately to the measured speed of the tachometer device.

It is still another object of this invention to provide in connection with lead-compensating mechanism, a reversing mechanism to maintain the lead compensation ahead of the target irrespective of the direction of movement of the target.

It is a further object of this invention to provide a mechanism which will also compensate for the ballistic deviations of the projectile and for deviations of the projectile caused by wind effects resulting from the position of the gun with respect to the flight path of the airplane.

Other objects of invention will become apparent from the following description taken in connection with the accompanying drawings in which:

Fig. 1 is a perspective view, partly in section, of a machine gun flexibly mounted in an airplane and incorporating the present invention;

Fig. 2 is an exploded perspective view of the mechanism constituting the invention; and

Fig. 3 is a cross-sectional view through the sight-changing mechanism.

Referring to the drawings, and particularly to

Fig. 1, there is shown a machine gun 1 mounted to pivot about a horizontal axis 2 and carried by a yoke 3 which in turn is fixedly mounted on a carriage member 4 rotatably slidably mounted on a guideway 5. The guideway 5 is integral with a body member 6 which, in the preferred embodiment of the invention, is an airplane. The guideway 5 and other stationary parts may be said to constitute a gun platform.

Coming now to the apparatus for maintaining the gun pointed with the desired lead, there is provided: (1) an apparatus for measuring the vertical component of the relative speed between the target and the gun platform and for correspondingly positioning the sight; (2) a device for mechanically measuring the horizontal component of the relative speed between the gun platform and the target and for correspondingly positioning the sight; (3) an apparatus for compensating for the ballistic deviations of the projectile; (4) apparatus for compensating for the deviation of the projectile resulting from the orientation of the gun with respect to the flight path of the airplane; and (5) reversing mechanism to maintain the lead compensation correction ahead of the target irrespective of the direction of movement of the target.

Still referring to Fig. 1, the apparatus for measuring the vertical component of relative speed between the gun platform and the target is contained in box 154 fastened to yoke 3 by means of bracket 155; the apparatus for measuring the horizontal component of relative speed between the gun platform and the target is contained in box 156 fastened to member 4 by bracket 157, and the sight-positioning mechanism is contained in box 158 suitably fastened to the gun. It is to be understood that all members are suitably supported and that bearings and thrust bearings are provided wherever necessary.

Mounted on the body of the gun 1 for universal movement with respect thereto is a sight 7 adapted to be positioned by the lead-predicting-and-compensating mechanism which will now be described in detail:

Referring to Fig. 2, there is shown integral with the gun 1, a curved rack 8 the axial center of which should coincide with the pivotal center 2 of the gun and with which a pinion 9 disposed on an operating shaft 10 projecting upwardly from the box 154 is adapted to mesh, to be driven thereby upon rotation of gun 1 about its horizontal axis 2. The driving of pinion gear 9 causes rotation of shaft 10 and gear 11 integral therewith and enclosed in the box 154. Gear 11.

in turn, meshes with gear 12 to drive the same along with shaft 13 and gear 14, gears 12 and 14 being integral with shaft 13. Gear 14 drivingly meshes with gear 15, the motion of which is imparted to shaft 16 and gear 17 integral therewith. Gear 17 meshes with gear 18, integral with shaft 19, which in turn is carried by block 20 to which is pivotally attached at the opposite ends thereof, arms 23 and 24 having weights 25 and 26 integral therewith, respectively, to constitute a tachometer. Attached to the arms 23 and 24 of the tachometer are a pair of cam elements 29 and 30 having predetermined cam slope characteristics. Riding on the cam surfaces of arms 29 and 30 is a saddle member 31 carrying a thrust member 32 freely rotatable with respect thereto as a result of the provision of antifriction bearings 33. Between the saddle member 31 and the cam surfaces of the arms 29 and 30 there are also provided antifriction bearings 34. Since the relative vertical position of the weight members 25 and 26 with respect to their respective pivot points is a measure of the speed of rotation of the tachometer, it follows that the tachometer may be used to measure the vertical component of the relative speed between the gun platform and the target when the gun is trained to follow the movement of the target, and that by the provision of suitable connecting mechanism, to be presently described, the sight may be so positioned as to compensate for the necessary lead. The cam surfaces on arms 29 and 30 must be so constructed as to result in given constant increments of movement of the saddle member in a vertical direction for given increments of measured rate resulting from changes in angularity of the arms 23 and 24 caused by operation of the tachometer.

Coming now to the mechanism responsive to the tachometer for changing the sight vertically to compensate for the vertical component of lead, thrust member 32 has integral therewith a shaft 35 slidably mounted in bearing member 36, suitably attached to box 154, and having integral therewith a flexible force-transmitting member 37. This member 37 extends into the box 156 and is connected to a slidably mounted frame member 38 having gear teeth 39 and 40 thereon. Tension spring 41 urges member 38 toward the right, as shown in Fig. 2 of the drawings, against the action of the tachometer. Meshingly engaged with gear teeth 40 is a spur gear 43 integral with shaft 44, which in turn is suitably rotatably mounted in frame member 45. Also integral with shaft 44 is a bevel gear 46 adapted to mesh with bevel gear 47 rotatably mounted on shaft 48. Suitable thrust means (not shown) carried by box 158, prevent longitudinal movement of bevel gear 47. Also carried by frame 45 is a spur gear 42 integral with shaft 49. Shaft 49 is, like shaft 44, suitably rotatably mounted in frame member 45 and has integral therewith a bevel gear 50. The frame member 45 is adapted to be shifted laterally, for a purpose to be more fully hereinafter explained, so that either gear 46 or 50 will be in driving engagement with gear 47 to rotate it in one direction or the other in response to reciprocation of member 38 under the action of the tachometer and spring 41. Carried by the sleeve part 51 of bevel gear 47 is a cam follower 52 (Fig. 3) received in a cam groove 53 in sleeve member 54. Sleeve member 54 is in turn slidably mounted on the part 51 of bevel gear 47 so that rotation of the bevel gear will result in a vertical displacement of sleeve member 54 in accordance with the characteristics of the

cam slot 53. Sleeve member 54 is provided with a shoulder part 55 adapted to be received in a correspondingly cut-away part in gear nut 56. Gear nut 56 is in turn slidably and rotatably mounted with respect to shaft 48 and is provided with a cam follower 57 received in cam slot 58 in cylindrical plug member 59 slidably, but non-rotatably, carried by shaft 48. The purpose of the cam follower 57 and cam surface 58 will be more fully explained hereinafter. Suitably connected to the upper end of cylindrical member 59 to be integral therewith and operated thereby is a member 60 having forked portions 61 received in a circumferential recess 48a in shaft 48. To prevent rotation of member 60 and, consequently, cylindrical member 59, there is provided a pair of pins 27 and 28. Vertical movement of member 59 results in a corresponding vertical movement of cam box member 60 as well as shaft 48 by reason of engagement of member 59 with recess 48a of shaft 48. Member 60 is provided with a horizontally curved slot 61a and a horizontal slot 62. Received in the vertical slot 61a is a rod member 63 provided with ear members 64 having a pin 65 therethrough, which in turn is received in slot 66 of clamping member 67 attached to one end of telescope 7. The other end of the telescope 7 is provided with a clamping member 68 having a pivotal connection 69 operatively received by yoke member 70, which, in turn, is mounted to rotate about a vertical axis in bearing member 71.

Referring now to the other end of the telescope, and particularly to Fig. 3 taken in conjunction with Fig. 2, shaft 63 is provided with a pair of washers 72 suitably connected thereto. Vertical movement of member 60 is transmitted to shaft 63 through the intermediary of these washers, while horizontal movement of shaft 63 is accomplished by means of portion 136a of pitman 136 fixedly connected to the upper end of the vertical shaft 48.

Having described the mechanism for changing the sight vertically to compensate for the vertical component of the lead, there will now be described the mechanism for compensating for the ballistic deviation of the projectile in a vertical direction.

Cam slot 81 (on gun 1 in Fig. 2) and formed in the segmental rack 8 has incorporated therein predetermined slope characteristics such as to compensate for the deflection of the projectile in a vertical plane due to the wind effect caused in part or entirely by movement of the airplane through the air.

Cam 91, located on the under side of member 5, has incorporated therein slope characteristics such as to compensate for the vertical deflection of the projectile due to the above-mentioned wind effect in any horizontal or azimuth position of the gun. These additional compensations are transmitted (as shown in Fig. 2) to the sight 7 by means of cam box member 60, member 59, gear nut 56, and cam follower 57 integral therewith and operatively received in cam slot 58 in member 59. Gear nut 56 is operated by rack 72 which combines the effect of cams 81 and 91, and may be referred to as a resultant rack, since there is transmitted thereto the algebraic sum of twice the linear movement of gear 73 plus the linear motion of rack 76.

Reciprocation of rack 72 to cause rotation of gear nut 56, and a consequent vertical movement of sight 7, is caused by a differential gear 73

carried by a yoke 74 and rotatable upon a bearing pin 75. Yoke 74 and differential gear 73, meshing with racks 72 and 76, is caused to move by two separate mechanisms now to be described. The first of these is a direct movement through flexible connection 77, operatively connected to follower bar 78, guided for reciprocal movement in bearing member 79 which is carried stationary with respect to the gun supporting bracket 3 and has a suitable bearing or operating projection 80 received in the cam slot 81 in rack 8 fixed to move with the gun. Rotation of the gun about its horizontal pivot 2 results in longitudinal movement of yoke member 74 under or against the action of spring 82 to cause reciprocation of rack 72. The second of these relates to mechanism for actuating rack 72 for the purpose of compensating for the vertical deflection of the projectile due to the azimuth position of the gun. This compensation is transmitted to rack 72 through differential gear 73 by rack 76, this rack having at one end thereof a roller 83 suitably mounted thereon and adapted to engage cam surface 84 of cam 85. A tension spring 86 urges the cam towards the right, as shown in Fig. 2, to its return position. The cam is urged towards the left through flexible connection 87 operatively connected to follower bar 88 suitably guided in bearing 89 carried by member 4 for reciprocatory movement. The follower bar 88 carries at the lower end thereof a follower 90 adapted to operatively engage cam surface 91 on member 5, the cam having, as previously stated, predetermined correction characteristics incorporated therein to compensate for the vertical deflection of the projectile due to the azimuth position of the gun.

While the characteristics of the compensating mechanism for vertical deflection due to the vertical position of the gun and the azimuth position of the gun are dependent upon the position of the gun, it is readily apparent that in order to properly compensate for lead in the proper direction to maintain the lead compensation ahead of the target irrespective of the direction of movement of the target, it is necessary to provide a reversing mechanism to obtain the desired results. This reversing mechanism will now be described. Referring again to Fig. 2, as previously described, frame member 45 is adapted to be shifted laterally to bring either gear 46 or 50 into driving engagement with gear 47 to rotate it in one direction or the other in response to reciprocation of member 38 under the action of the flyball governor and spring 41. Whether gear 46 or gear 50 is desired to be in engagement depends upon the desired direction of lead compensation. In order to suitably reciprocate frame 45 to bring the desired gear into engagement with gear 47, there is provided a flexible connection 93 operatively connected to lever 94 suitably pivotally mounted upon pin 95 and having a pointed portion 96 adapted to suitably engage with the teeth of gear 47. Operatively connected to the extreme right end of frame 45 is a spring 97 adapted to urge the frame toward the right. Lever 94 therefore moves to the right or the left, depending upon the direction of rotation of gear 47, and moves frame member 45 toward the left to bring gear 46 into engagement with gear 47 in one position of the lever, or gear 50 into operative engagement with gear 47 in accordance with the other position of the lever. Lever 94 has operatively associated therewith springs 98 and

99 for the purpose of equalizing the movement thereof.

Apparatus will now be described for mechanically measuring the horizontal component of the relative speed between the gun and the target and for correspondingly positioning the sight. In the normal installation of a flexible gun in an airplane, the gun is mounted on a suitable rotating turret which permits the gun to be positioned at any azimuth angle. As shown in Fig. 1, the machine gun is carried by yoke 3 mounted on carriage member 4, which in turn is slidably mounted on guideway 5. The guideway 5 is suitably fastened to the body of the airplane 6 and has fastened thereto a large annular gear member 100 and a trackway 101. Spur gear 102 is adapted to mesh with gear 100 and, upon movement of the gun about a vertical axis, causes rotation of gear 103, shaft 104, gears 105 and 106, and shaft 107. This train of gears constitutes a suitable mechanism for stepping up the speed of rotation of the gun to a speed that will reduce the necessary size of the rate-measuring device. Integral with shaft 107 is a block 108 having pivotally attached thereto at the ends thereof a pair of governor arms 109 and 110 provided with suitable governor weights at the ends thereof. Governor weight 111 is shown at the end of governor arm 110, and it is to be understood that a similar weight is intended at the end of arm 109, it being omitted to avoid obscuring other details in the drawings. The governor arms are provided with cam members 112 and 113 respectively, having predetermined characteristics. Operatively engaging these cam members is a saddle member 114 carrying a shaft 115. Between the saddle member and the cam members there are provided suitable antifriction bearing members 116. The upper end of shaft 115 is rotatably mounted in the saddle member 114 and is provided with a thrust bearing 117. Between the thrust bearing and the saddle member there are provided suitable antifriction bearings 118. Shaft 115 is suitably slidably supported in a bearing member 119, and has operatively connected thereto a flexible member 120 suitably connected to a double rack member 121. This double rack member is urged toward the left by means of spring 122 and is operatively positioned by reciprocation of shaft member 115 in response to the action of the flyball governor, which in turn serves as a means for measuring the rate of movement of the gun about a vertical axis. Operatively associated with double rack member 121 is a frame member 123 carrying a pair of spur gears 124 and 125 adapted to mesh with the teeth of rack 121. Integrally united with spur gear 124 to rotate therewith is a bevel gear 126, while a bevel gear 126a is integrally united with spur gear 125 to rotate therewith.

As will be more fully described hereinafter, frame 123 is adapted to reciprocate so that either gear 126 or 126a will be in operative engagement with bevel gear 127. Gear 127 is integral with one end of shaft 128, at the other end of which is provided a spur gear 129 adapted to mesh with rack 130. Rack 130 is provided at one end thereof with a yoke member 131 for rotatably supporting a differential gear 132. Differential gear 132 is adapted to mesh with racks 133 and 134. Rack 133 is in meshing engagement with gear 135 integral with and carried by shaft 48. Gear 135 is of substantial width so that it will remain in mesh with rack 133 irrespective of vertical move-

ment of gear 135 with shaft 48. The upper end of shaft 48 is provided with a pitman 136 having a slot 137 for receiving shaft 63. It is readily apparent that movement of the gun about a vertical axis will be measured, with respect to the speed of movement, by the flyball governor, and that the sight 7 will be moved by an amount corresponding to the measured speed through the mechanism just described.

A reversing mechanism similar to the reversing mechanism previously described and used in connection with the means for compensating for the vertical component of the lead will now be described. As previously stated, either gear 126 or 126a is adapted to mesh with bevel gear 127, depending upon the position of frame 123. This frame is urged toward the left by spring 138 operatively associated with one end thereof. The other end of the frame has operatively connected thereto a flexible member 139, which in turn is connected to lever 140. This lever is pivotally mounted upon pin 141 and is provided with a pointed portion 142 adapted to suitably engage the teeth of the annular gear member 100. Lever 140 is pivoted to the right or to the left, depending on the movement of the gun with respect to the trackway, frame member 123 being moved accordingly. Springs 143 and 144 are provided to equalize the movement of the levers.

To compensate for horizontal deflection due to horizontal or azimuth positions of the gun, there is incorporated in cams 91 and 149 horizontal-deflection-compensating characteristics. Cam 91 is carried by trackway 5 and has associated therewith a cam follower 145 rotatably mounted on one end of follower bar 146 which, in turn, is suitably supported for reciprocatory motion in bearing 147 carried by member 4. Cam follower 145 engages cam 91 and responds to variations therein. Attached to the other end of follower bar 146 is a flexible cable 148 which, in turn, is attached to the cam member 149. Associated with cam member 149 to be operated thereby is a rack 134 carrying a roller 151 in operative engagement with the cam. Rack 134 is in operative engagement with gear 132 and transmits the compensating correction to this gear and, consequently, to the resultant rack 133. The resultant rack therefore transmits to the sight the algebraic result of the linear displacement due to the ballistic cams plus twice the linear displacement of gear 126. This two-fold displacement of lead is compensated for by the selection of a suitable gear train which halves the distance moved by rack 130.

From the above description it is readily apparent that, from the mechanism shown and described, the gun will be maintained in alignment with the predicted position of a target by merely training the gun so that the target is maintained in the gun sights.

In this respect, it has been shown that the gun sight is adjusted by the tachometer rate-measuring devices and the reversing mechanisms and connecting mechanism for horizontal and vertical components of lead in the proper direction.

It has also been shown that deflection corrections for ballistics have been applied to the sights, these corrections being necessary because of ballistic deviations—depending upon the position of the gun with respect to the flight path of the airplane—resulting from gravity, drift due to air pressure, and the motion of the projectile due to its gyroscopic effect which is called windage jump. The vertical components of the deflection

for azimuth position of the gun have been compensated for by cams 85 and 91; the vertical component of deflection for the vertical position of the gun has been compensated for by cam 81; and the horizontal component of deflection due to azimuth position of the gun, by cams 92 and 149.

Although a single preferred embodiment of the invention is shown, it is to be understood that the invention may take various forms, it being intended to be limited only by the appended claims.

We claim:

1. In combination with a gun mount and a universally mounted gun thereon, adjustable sighting means therefor, and means operatively associated with said gun, mount, and sighting means for constantly predicting the future position of a moving target, means angularly adjusting the sighting means relatively to the gun to maintain said gun aimed to hit said future position, including centrifugal tachometer means operable by relative movement between the gun and its mount for calculating the relative speed of said target with respect to said gun mount, and supplemental means operable by relative movement between the gun and its mount, and connected to said sighting means for adjusting said sighting means to compensate for the ballistic deviation of the projectile.

2. In combination with a universal gun mount carrying a gun for angular movement in elevation and in azimuth, relatively adjustable sighting means for said gun connected for movement thereby, and means between the gun and its mount responsive to angular movements of said gun with respect to its mount for adjusting said sighting means so that by maintaining the sighting means in alignment with a relatively moving target the gun will be aligned with the point of coincidence of said target and the projectile fired from said gun, said last named means comprising centrifugal tachometer means operatively connected between the gun and its mount, and arranged to be actuated by angular movement of said gun with respect to its mount, for measuring the rate of said movement therebetween, operating means between the centrifugal tachometer means and the gun sighting means, responsive to movement of said centrifugal tachometer means for adjusting said sighting means relatively to the gun, and separate compensating sight adjusting means operatively positioned between the gun and its mount, and responsive to adjustment of the angular position of said sighting means with respect to said mount for adjusting the sighting means to compensate for horizontal deflection of the projectile due to azimuth position of the gun and the ballistic deviation of the projectile.

3. In combination with a universal gun mount adjustably carrying a gun for angular movement in elevation and in azimuth, universally mounted adjustable sighting means on the gun, and operating means between said gun and its mount responsive to adjustment of said gun with respect to the mount for relatively adjusting the sighting means incident to relative movement of the gun on its mount, so that by maintaining the sighting means in alignment with a relatively moving target, the gun will be aligned with the projected point of the coincidence of said target and a projectile fired from said gun, said last named means comprising centrifugal tachometer means operatively connected between the gun and

mount responsive to elevational movement of said gun with respect to said mount for calculating the rate of elevational movement thereof, a rack operated by said centrifugal tachometer means, means operated by said rack and operatively connected to the sighting means for angularly moving said sighting means in elevation with respect to said gun, a second centrifugal tachometer means operatively connected between the gun and its mount, operated by azimuth movement of said gun with respect to said mount for calculating the rate of movement thereof in azimuth, a second rack operated by said second centrifugal tachometer means, and means between said second rack and sighting means operated by said second rack for relatively moving said sighting means in azimuth relatively to the gun in proportion to the angular movement of the gun in azimuth with respect to said mount.

4. In combination with a universal gun mount carrying a gun for angular movements in elevation and in azimuth, adjustable sighting means on said gun, means responsive to movement of said gun for adjusting said sighting means so that, by maintaining said line of sight in alignment with a relatively moving target, the gun will be aligned with the predicted point of coincidence of said target and the projectile fired from said gun, said last named means comprising a plurality of centrifugal tachometer means driven by and responsive to horizontal and vertical angular movements respectively of said gun with respect to said mount for measuring the rates of movements thereof, cam arms carried by said centrifugal tachometer means, rack means connected to said cam arms to be reciprocated by said cam arms proportionate to the angular rate of movement of the gun as measured by said tachometer means, frame means, first and second gears carried by the frame means, each gear meshing with the rack, a third gear, said frame means being shiftable to selectively engage one or the other of said first and second gears with said third gear, a reciprocating sleeve, cam means through which rotation of said third gear reciprocates said sleeve, a connection between said sleeve and said sighting means whereby reciprocation of said sleeve operates said sighting means, and cooperating means controlled by angular movement of the gun in one plane and responsive to the direction of movement for shifting said frame means to bring a selected gear of one of said first and second gears into mesh with said third gear.

5. In combination with a universal gun mount carrying a gun mounted for relative angular movements in elevation and in azimuth, an adjustable sight on said gun, and means responsive to angular movements of said gun for adjusting the sight with respect to the gun so that, by maintaining said sight in alignment with a moving target, the gun will be aligned with the predicting point of coincidence of the target and the projectile fired from the gun, said last named means comprising centrifugal tachometer means connected between the gun and its mount and operable by relative movement between the gun and its mount for measuring the rate of angular movement of the gun about a horizontal axis; cooperating rack, gear and cam means operatively connecting said centrifugal tachometer means and said sight, for adjusting the sight with respect to the gun in response to operation of the centrifugal tachometer means, a second centrif-

ugal tachometer means connected between the gun and its mount, operable by relative movement between the gun and its mount for measuring the rate of horizontal angular movement of the gun about a vertical axis; cooperating rack, gear and cam means operatively connecting said second centrifugal tachometer means with said sight for operatively positioning the sight with respect to the gun in response to operation of said second centrifugal tachometer means, supplemental sight adjusting means between the sight, the gun, and its mount, for positioning the sight with respect to the gun to compensate for ballistic corrections, said supplemental means including means operatively associated with the second tachometer means for compensating for a vertical deflection of the projectile due to azimuth position of the gun, means operatively associated with the first tachometer means compensating for vertical deflection of the projectile due to vertically adjusted positions of the gun, and means operatively associated with the second tachometer means for adjusting the sight with respect to the gun to compensate for horizontal deflections of the projectile, due to azimuth position of the gun.

6. In combination with a universal gun mount carrying a gun for angular swinging movements in elevation and in azimuth, an adjustable sight on said gun, and means responsive to swinging movements of the gun for adjusting said sight with respect to the gun, so that by maintaining said sight in alignment with a relatively moving target, the gun will be aligned with a predicted point of coincidence with the target and the projectile fired from the gun, said last named means comprising a first centrifugal tachometer means connected between the gun and its mount, responsive to swinging movement of the gun about a horizontal axis for measuring the relative rate of movement thereof with respect to a fixed portion of the gun mount, a rack operatively connected with said first centrifugal tachometer means to be moved thereby in response to the operation thereof, a shiftable frame member including two pairs of opposed gears carried by said frame members, one gear of each pair being in operative engagement with said rack, a third sight adjusting gear means, each of the other gears of each of said pairs of gears being constructed and arranged to be selectively brought into operative engagement with said third sight adjusting gear means upon shifting movement of said frame in respective opposite directions, means responsive to directional movement of said gun with respect to its mount, and operatively connected to said shiftable frame for shifting said frame to engage one or the other of said last mentioned frame gears, and means operatively connected between said third gear and said sight for adjusting the same with respect to the gun.

7. A device as recited in claim 6, and further including cam means between the gun and mount operable by relative movement therebetween, having predetermined ballistic corrections incorporated therein and arranged in cooperative relation with said adjustable sight, including means between the gun, its mount, and the sighting means, responsive to angular positions of said gun on its mount for adjusting the sighting means in response to the said cam corrections.

LOUIS W. GREENBLATT, JR.
GUY T. BIXBY.
